A. F. McDONNELL

CLOSURE FOR BOTTLES

Filed April 17, 1928

FIG. 2

FIG. 1

FIG. 3

INVENTOR
ANTHONY FRANCIS McDONNELL
BY
Mason, Fenwick + Lawrence
ATTORNEYS

UNITED STATES PATENT OFFICE.

ANTHONY F. McDONNELL, OF DUNMORE, PENNSYLVANIA, ASSIGNOR OF ONE-THIRD
TO WILLIAM ALOYISOUS QUINN, OF SCRANTON, PENNSYLVANIA.

CLOSURE FOR BOTTLES.

Application filed April 17, 1928. Serial No. 270,748.

My invention relates more particularly to that class of closures for bottles, jars, and other rigid containers in which the bottle neck, for example, is enlarged by a peripheral bead or otherwise around the mouth of the bottle, and the cap, for example, that known as the "Crown" cap, which is provided with a cork or other lining in its crown to seal the mouth of the bottle, is crimped or compressed to form a contracted rim bound tightly around the neck of the bottle, and secured against displacement thereon by the enlargement around the mouth of the bottle.

The Crown cap has heretofore generally been removed when desired by a special tool for the purpose which often distorts the cap in removal so that it cannot be used again even for temporarily closing the container, as when only part of the contents is to be used at a time.

The primary object of my invention is to provide a neck for bottles, jars, and similar containers so formed that the cap, when crimped or compressed thereon, as by means of the ordinary crimping machines in common use, will be securely held in place against leakage and displacement and yet can be easily removed by hand without the use of any tool, and after removal can be easily replaced on the neck for temporarily closing the container when only part of its contents have been used.

To this and other ends, my invention consists broadly of a container, for example, a bottle, having a neck formed with peripherally and upwardly inclined beads or shoulders to engage inward projections, or some of the corrugations, if a Crown cap, on the inside of the rim thereof and lift the cap off the neck as the cap is turned, and with upwardly and outwardly inclined parts by which the rim of the cap, when crimped or contracted around the neck, is locked in place and which, when the cap is turned by hand, will act to expand the rim and ease the lifting of the cap off the neck.

My invention also consists more specifically, in forming the peripherally and upwardly inclined shoulders on the upper sides of beads raised around the neck of the bottle, the undersides of which when the several beads overlap, serve with the outwardly inclined parts of the neck, to engage the inward cap projections and lock the cap in place.

The inclined shoulders on the neck may also be formed of inclined grooves in the neck.

The broad invention and the specific form thereof above briefly stated, are not claimed herein but are described and claimed in a separate application for patent filed by me April 17th, 1928, Serial No. 270,750.

The present application is specifically for another specific form of my broad invention described but not claimed in my said other application, and consists in making the outer sides of the inclined beads instead of or together with the body of the neck between the same, inclined outwardly and upwardly, so that the inclined parts of the neck formed by said outer sides of the beads will serve to lock the cap in place when crimped or contracted thereon and to spread the rim of the cap and ease its lifting and removal when turned and lifted by the upwardly and peripherally inclined shoulders formed by the upper sides of the beads.

In order that my invention may be fully understood, I shall first describe in detail the mode in which I at present prefer to carry this invention into practice, and then particularly point out the invention in the claim.

Reference is to be had to the accompanying drawings forming part of this application in which like parts are designated by the same numbers in all the figures.

Figure 1 is a sectional side view of a bottle neck with Crown cap embodying my invention.

Figure 2 is a cross sectional view of the same on the line 2—2, Figure 1.

Figure 3 is a side view of said bottle neck. In the drawings, 19 designates the bottle neck and 18 the body thereof which may be cylindrical as shown or slightly inclined upwardly and outwardly.

The bottle neck is formed with beads, the upper sides 21 of which are inclined upwardly and peripherally toward the mouth 23 of the bottle to form upwardly and peripherally inclined shoulders.

The outer sides 22 of the beads are inclined upwardly and outwardly toward the mouth of the bottle to form upwardly and outwardly inclined parts of the neck.

When the rim 24 of a Crown cap 25, for example, is crimped or contracted around the neck 19 thus formed, the upwardly and

outwardly inclined parts 22, co-operate with the inward projections formed by the corrugations on the inside of the rim 24, some of which enter the grooves between the 5 beads, to lock the cap securely on the neck.

When the cap is turned by hand some of the internal projections on the rim 24, engage and ride upward on the upwardly and peripherally inclined shoulders 21 of the 10 beads and lift the cap, which is slightly flexible, off the neck.

At the same time the upwardly and outwardly inclined parts 22 of the beads on the neck act to spread the flexible rim 24 15 of the cap and facilitate the removal of the cap from the neck.

As the cap, being flexible, is not unduly distorted by the lifting and spreading process, it, after removal, can be easily slipped 20 over the cap-expanding and securing parts 22 and replaced on the neck temporarily to cover the remaining contents of the bottle when only a part thereof has been used.

It is evident that this improved form of 25 container neck may be used with other caps than Crown caps, which have a rim adapted

to be contracted below the mouth of the bottle and interior projections on the rim which will engage the upwardly and peripherally inclined lifting shoulders on the 30 neck.

It is also evident that other changes may be made in the practice of my invention without departing from the boundaries thereof as defined by the following claim. 35

I claim as my invention:

A bottle or other container having its neck formed with beads whose upper sides form shoulders inclined upwardly and peripherally toward the mouth and whose outer 40 sides form parts inclined upwardly and outwardly toward the mouth, so that the upwardly and peripherally inclined shoulders will engage the inward projections of a cap crimped or contracted thereon and lift the 45 cap off the neck when turned, and the outwardly inclined parts will assist in locking the cap when contracted on the neck, and ease its lifting by the shoulders when it is turned. 50

In testimony whereof I affix my signature.

ANTHONY F. McDONNELL.
